DESIGN FOR A SPECTACLE CASE OR THE LIKE

Emanuel Nathan, Maplewood, N. J.

Application May 25, 1942, Serial No. 106,991

Term of patent 7 years

To all whom it may concern:

Be it known that I, Emanuel Nathan, a citizen of the United States, residing in the township of Maplewood, in the county of Essex, and State of New Jersey, have invented a new, original, and ornamental Design for a Spectacle Case or the like, of which the following is a specification, reference being had to the accompanying drawing, forming a part thereof.

In the drawing,

Fig. 1 is a plan view of a spectacle case or the like, showing my new design,

Fig. 2 is a rear elevational view of the same, and

Fig. 3 is an end view of the same.

I claim:

The ornamental design for a spectacle case or the like, as shown.

EMANUEL NATHAN.
